UNITED STATES PATENT OFFICE.

EDWARD B. MOSSER, OF TROOPER, PENNSYLVANIA.

DESIGN FOR A STOCKING.

Application filed March 8, 1928. Serial No. 25,767. Term of patent 14 years.

To all whom it may concern:

Be it known that I, EDWARD B. MOSSER, a citizen of the United States, residing at Trooper, in the county of Montgomery and State of Pennsylvania, have invented a new, original, and ornamental Design for Stockings, of which the following is a specification, reference being had to the accompanying drawing, forming a part thereof.

Figures 1 and 2 are respectively side and rear elevations of a stocking, illustrating the location and extent of ornamentation of my new design on a stocking; and Figure 3 is a view showing the design feature at the heel of the stocking shown in Figures 1 and 2 in enlarged detail.

I claim:

The ornamental design for a stocking, as shown.

EDWARD B. MOSSER.
